UNITED STATES PATENT OFFICE.

ASA L. BENNINGTON, JACOB S. BENNINGTON, JR., AND JOHN F. BENNINGTON, OF LA HARPE
ILLINOIS.

BROODING-COOP.

No. 858,643.

Specification of Letters Patent.

Patented July 2, 1907.

Application filed March 14, 1907. Serial No. 802,342.

To all whom it may concern:

Be it known that we, ASA L. BENNINGTON, JACOB S. BENNINGTON, JR., and JOHN F. BENNINGTON, citizens of the United States, residing at La Harpe, in the county 5 of Hancock and State of Illinois, have invented certain new and useful Improvements in Brooding-Coops; and we do declare the following to be a full, clear, and exact description of the invention, such as will enable others skilled in the art to which it appertains to make 10 and use the same.

This invention relates to improvements in brooding coops.

The object of the invention is to provide a brooding coop constructed and arranged from a series of sections 15 adapted to be detachably connected together, whereby the same may be taken apart to provide for the compact packing of the coop for shipping or storing purposes, and to permit the coop to be readily cleaned.

20 A further object is to provide a coop of this character which will be simple, strong and durable in construction, and having means arranged therein to provide for ventilation of the coop.

With these objects in view, the invention consists of 25 certain novel features of construction, combination and arrangement of parts as will be more fully described and particularly pointed out in the appended claims.

In the accompanying drawings, Figure 1 is a perspective view of a coop constructed in accordance with the invention; Fig. 2 is a vertical, longitudinal sectional view; and Fig. 3 is a vertical, cross sectional view of the same. Fig. 4 represents a horizontal section on the line 4—4 of Fig. 1.

30 Referring more particularly to the drawings, 1 denotes the coop, which consists of a bottom plate or section, 2, the edges of which are bent downwardly to form flanges 3, with which are adapted to be detachably engaged inwardly and upwardly bent flanges, 4, formed on the lower edges of the front, rear and side pieces of the coop. The front piece, 5, and the rear piece, 6, are preferably 35 provided with D-shaped upper ends to form supports for the inclined roof sections, 7.

The meeting edges of the front and rear sections, 5 and 40 6, and the side section or sections, 8, at the corners of the coop are provided with detachable, interlocking joints, 9, whereby said sides and end sections are removably connected together.

45 The upper inclined edges of the front, and rear section and the engaging edges of the roof sections are provided with detachable, interlocking joints, 10, whereby 50 said roof sections may be slipped downwardly out of engagement with the upper edges of the front and rear sections. The upper edges of the side sections are provided with overhanging or downwardly projecting flanges, 12, which are adapted to be engaged by in-

wardly projecting flanges, 13, on the lower edges of the 55 roof sections when the latter are arranged in position on the coop.

The upper meeting edges of the roof sections, 7, are provided with upwardly bent flanges, 14, which are engaged with each other when the roof sections are arranged in position on the coop. Adapted to be engaged with the flanges, 14, of the roof section is a cap strip, 15, which is preferably formed of a strip of galvanized metal bent or folded lengthwise upon itself to fit down over the flanges 14 of the roof sections. Through the 60 sides of the cap strip and the flanges 14, are formed aligned bolt holes in which are adapted to be inserted fastening bolts, 16, by means of which the roof sections are detachably fastened together, thereby holding the entire coop in a set-up position. If desired a handle or 65 bail, 17, may be provided and connected at its lower ends to the cap strip, 15, and flanges, 14, of the roof section, as shown.

In the front end section, 5, is formed a door opening, 18, which is adapted to be closed by one of a series of 70 doors arranged on the front end of the coop. The doors for closing the opening, 18, preferably consist of a solid sheet metal door, 19, a wire netting door, 20, and a slatted or barred door, 21, said doors being pivotally mounted at their lower inner corners upon a common pivot bolt, 75 22, which is arranged in the end of the coop, and in the lower end of a guide bar 23, which is secured to said end and spaced therefrom, as shown. The doors, 19, 20 and 21, are supported in an open or closed position by means of a trough-shaped flange, 24, secured to the front side of 80 the coop adjacent to the bottom of the same. The doors when in a closed position are adapted to be engaged and held by a spring metal clip, 25, secured to the front end of the coop, as shown. In the rear end of the coop adjacent to the upper end thereof, is formed a 85 series of ventilating openings, 26, said openings being preferably formed by cutting semi-circular slits in the metal forming the rear end of the coop and bending the cut portion of the metal outwardly, thereby forming the openings, 26, which are protected by the outwardly 90 projecting or inclined semi-circular piece of metal.

The coop may be formed of any suitable material, but is preferably formed of galvanized sheet metal, the arrangement being such that a perfectly sanitary vermin-proof coop is provided. The coop is particularly adapted for brooding purposes, but may be used as a house 95 for all varieties of fowls, or other animals.

From the foregoing description, taken in connection with the accompanying drawings, the construction and operation of the invention may be readily understood 100 without requiring a more extended explanation.

Various changes in the form, proportions and the minor details of construction may be resorted to with-

out departing from the principle or sacrificing any of the advantages of this invention, as defined in the appended claims.

Having thus fully described my invention, what I claim as new, and desire to secure by Letters-Patent, is:

1. A coop of the character described, comprising a bottom plate or section having downwardly projecting flanges arranged on its outer edges, flanged rear and side sections or pieces having flanges on their lower ends adapted to engage the flange on said bottom plate, interlocking joints formed at the meeting edges of said flanged rear and side sections at the corners of the coop, inclined roof sections, interlocking joint connections between the edges of said roof sections and the front, rear and side sections of the coop, and means to connect the upper edges of said roof sections together to secure the sections of the coop in a set-up position, substantially as described.
2. A coop of the character described, comprising a bottom plate or section having downwardly projecting flanges arranged on its outer edges, rear and side sections or pieces having flanges on their lower ends adapted to engage the flange on said bottom plate, interlocking joints formed at the corners of the coop, inclined roof sections, interlocking joint connections between the edges of said roof sections and the front, rear and side sections of the coop, upwardly projecting engaging flanges formed on the upper edges of said roof sections, a cap strip adapted to be engaged with and to cover said flanges, and a fastening bolt adapted to be inserted through aligned openings in said cap strip and roof flanges, whereby the same and the side sections of said coop are secured together in a set-up position, substantially as described.
3. A coop of the character described, comprising a bottom plate or section having downwardly projecting flanges arranged on its outer edges, flanged rear and side sections

or pieces having flanges on their lower ends adapted to engage the flange on said bottom plate, interlocking joints formed at the corners of the coop, inclined roof sections, interlocking joint connections between the edges of said roof sections and the front, rear and side sections of the coop, a bail or handle connected to said cap strip and flanges, and a series of doors adapted to close over a door opening in one end of said coop, substantially as described.

40

4. A coop of the character described, comprising a bottom plate or section having downwardly projecting flanges arranged on its outer edges, flanged rear and side sections or pieces having flanges on their lower ends adapted to engage the flange on said bottom plate, interlocking joints formed at the corners of the coop, inclined roof sections, interlocking joint connections between the edges of the said roof sections and the front, rear and side sections of the coop, upwardly projecting engaging flanges formed on the upper edges of said roof sections, a cap strip adapted to be engaged with and cover said flanges, fastening bolts adapted to be inserted through aligned bolt holes in said cap strip and flanges, a solid door, a wire netting door and a slatted door pivotally connected at their lower inner corners upon a pivot bolt on the front end of said coop, whereby said doors may be swung over a door opening in said end, a guide bar to hold the inner edges of said doors in place, a spring clip to hold the outer edges of the same when in closed position, and a supporting flange to support said door in a closed or open position, substantially as described.
